UNITED STATES PATENT OFFICE.

IRVING K. BAXTER, OF UTICA, NEW YORK, AND CHARLES F. BARRETT, OF SPRINGFIELD, MASSACHUSETTS, ASSIGNORS TO THE STANDARD VACUUM CLEANER COMPANY, OF BRIDGEPORT, CONNECTICUT, A CORPORATION OF CONNECTICUT.

DESIGN FOR A CASING FOR PORTABLE SUCTION CLEANING APPARATUS.

41,007.

Specification for Design. Patented Nov. 29, 1910.

Application filed July 19, 1910. Serial No. 572,751. Term of patent 14 years.

To all whom it may concern:

Be it known that we, IRVING K. BAXTER, a citizen of the United States, residing at Utica, in the county of Oneida and State of New York, and CHARLES F. BARRETT, also a citizen of the United States, residing at Springfield, in the county of Hampden and State of Massachusetts, have invented a new, original, and ornamental Design for a Casing for Portable Suction Cleaning Apparatus, of which the following is a specification, reference being had to the accompanying drawing, forming a part thereof.

Figures 1 and 2 are side elevations illustrating opposite sides of the invention. Fig. 3, is a view in perspective.

We claim:

The ornamental design for a casing for a portable suction cleaning apparatus, as shown.

IRVING K. BAXTER.
CHARLES F. BARRETT.
